UNITED STATES PATENT OFFICE.

JACOB B. CURRIER, OF LOWELL, MASSACHUSETTS, ASSIGNOR TO THE CURRIER TELEPHONE BELL COMPANY, OF MASSACHUSETTS.

ELECTRIC CALL.

SPECIFICATION forming part of Letters Patent No. 272,862, dated February 27, 1883.

Application filed May 15, 1880. (No model.)

To all whom it may concern:

Be it known that I, JACOB B. CURRIER, of Lowell, in the county of Middlesex and State of Massachusetts, have invented a new and 5 useful Improvement in Electric Calls, of which the following is a specification.

My invention relates to that class of electric calls which are formed by a series of pendulums of different lengths placed respectively 10 at different stations upon an electric circuit, and each provided with a bell to be sounded by the operation of a vibratory or undulatory electric current passing through the magnets of the pendulums, and corresponding in time 15 of vibration with that of the pendulum of the bell to be sounded. Such a series of alarm mechanisms is shown in the German patent of Maron, No. 1,944 of 1877, and in my application of November 10, 1879, for patent on electric calls; and it consists in combining with such pendulum and its magnet, to be put in 20 operation by the synchronous vibratory electric current, of a bell and a striker, and a latch or stop mechanism for such bell-striker, such 25 latch or stop mechanism to be operated to release and engage with the bell-striker by means of the vibrating pendulum, substantially as hereinafter described.

The object of my invention is to provide a 30 mechanism which will be actuated by the ordinary electric current used in telegraphing or telephoning to give a better and more powerful alarm than is now given by such current, to register or indicate that an alarm has been 35 given, and to provide a mechanism in which the power will be renewed by the necessary action of adjustment for use by the operator.

The nature of the invention will fully appear from the subjoined description, when considered with reference to the drawings forming 40 part of this specification.

Figure 1 is a front elevation of my device with the knob on the alarm removed. Fig. 2 is a side elevation, showing the indicator attachment. Fig. 3 shows an electric circuit provided with a calling mechanism at one station for making and breaking the electric circuit, and a series of pendulum-alarms at other stations on the line, provided with the bell, 45 auxiliary hammer, and latch, constructed according to my improvement. Fig. 4 repre-

sents a side view of a circuit-breaking mechanism for operating the alarms. Fig. 5 represents a top view of the same. 55

Similar letters of reference indicate like parts throughout the different views.

In Fig. 1, *a* is a frame, upon which is secured an electro-magnet, *A*, in the usual manner. 60

b is an adjustable bar, upon which hangs at point *c* the pivot (another being opposite) of the armature *i*, the bar *b* being adjusted and held in its position by the spiral spring *d* and nut *e*. 65

f is a portion of the case of the complete instrument. 70

g is a screw passing through the case *f* into the frame *a*, and is used to adjust the distance between the armature *i* and its magnet, and also between the weight *m* of the vibrator *C* and the end *h* of the rod *q*, as may be desired. The vibrator *C* is connected to the armature *i* at the lower end of the same by a short, thin, flexible metallic strip, *k*, and consists of a rod, 75 *l*, and weight *m*.

D is a stop-lever, pivoted at *n* to an arm, *t*, of the stud, which supports the bell *B*, and which lever is connected by a pivotal joint, *p*, to the rod *q*, the rod being supported by passing through the aforesaid stud. The lever *D*, when at rest, is held in its position by the superior weight of the end of the same marked *D*. The pin and slot at *r* limit the movement of the lever. When the vibrator *C*, Fig. 1, is 80 in motion and its weight *m* strikes the end *h* of the rod *q*, it depresses the lever *D* at the end *s* and liberates the hammer *F* of the alarm-movement. 85

In Fig. 3, *G*⁴ *G*⁴ represent the grounds of an electric circuit; *Z*, the battery; *X*, the central station, and *Y*¹ *Y*² *Y*³ three other stations on the circuit provided with my improved alarm. The calling-machine is placed at station *X*. This machine is intended to make 90 and break the circuit as desired in the different times required for actuating the pendulums *m m* at the respective stations.

C is a cylinder whose revolutions are controlled by clock-work, and is similar to that 95 shown in my patent of December 20, 1881, No. 251,097. Around the cylinder, and at right angles with its axis, are rows of pins, as at *G* 100

G' G² and J J J, the number of pins in a row differing from each other, and the pins in any one row being equidistant from each other.

l e is a lever that vibrates upon shaft c e and when at rest presses by the superior weight of the end i j against the metallic bar h³. This bar h³ is insulated from the other parts of the device by being inserted in the wooden bar f², which wooden bar swings at one end upon shaft c e, and is supported and adjusted by means of the screw and slot s p at the other end. The bar h³ is connected with one end of the line of an electric circuit and the shaft c e with the other. The lever l e also slides back and forth upon shaft c e, and can be so adjusted and held in position that it will come in contact with any desired row of pins in the cylinder C y. When the position of the lever l e has been so adjusted—as, for instance, row G and the cylinder C y is caused to revolve—the pin G' lifts the end i j of the lever l e and separates the lever from the bar h³, thus breaking the electric circuit. After the pin G' has reached the position of pin G² the lever falls to its former position, thus completing the circuit again. The cylinder C y being rotated at a regular speed and the pins being arranged as described, each row will act upon the lever l e a different but definite number of times during any given period, and the lever l e will, when operated upon by any one row of pins, make and break the circuit in a different interval from that which it does when operated upon by any other. The lever l e is retained in position to be operated upon by any one row of pins desired by the bar a⁴, one end of the lever rising and falling in one of the slots marked 1 2 3 4. When it is necessary to change it to be acted upon by another row of pins, the end working in the slots being depressed, the lever may be slid upon its shaft and allowed to fall into place with its shorter end in another slot.

In Figs. 1 and 2 the metallic plate M is connected at the end l n with one end of the line of an electric circuit, and is connected by spring N, through the frame of the alarm-movement to point l o, with the other end of the line, thus completing the circuit. The circuit is broken by that portion of the winder and circuit-breaker marked h² (represented in section through line Y of Fig. 2 in Fig. 1) being pushed through the opening O p in plate P l, and pushing back the spring N from its contact with plate M. The winder and circuit-breaker C W slides back and forth upon the shaft S h of the alarm-movement, and by means of the pin P n and slot S l is held in position to wind up the alarm-movement. The winder and circuit-breaker C W is held away from the plate P l by the spiral spring k pressing against the end of the shaft S h. The same result may also be obtained by projecting the end of the spring N through the opening O p in the plate P l. When the alarm-movement is wound up the winder and circuit-breaker C W is in position to break the circuit by pressing upon the knob V. In

this position the knob V is provided with a slot, V S, or other mark on the top edge of the same, which serves as an index, which index, by any subsequent change of position, indicates that an alarm has been struck since its last adjustment, thus enabling the person observing the instrument to know that a call has been given since its last adjustment, and by calling the central office he can learn who called him and indicate that he is in attendance to answer.

The operation of my device may be described as follows: The operator at the central office or at some station on the line connected with the device makes and breaks the circuit in intervals of time corresponding to the pendulum vibration of the vibrator C, or nearly so, so that the electro-magnet may act on the armature on the vibrator C at recurring intervals in proper time to accelerate the action of the vibrator C as a pendulum, to constantly increase the arc through which the weight m swings in equal times. When the arc reaches the end h of rod q h the weight m comes in contact with it and releases the bell-hammer F, and continues to release it by repeated blows upon the rod q h of the weight m, so long as the vibratory electric current continues to operate the vibrator C by its synchronous pulsations through the magnet A. The bell-hammer F is operated by means of a gearing driven by a spring or weight and connected to the axis, upon which it swings in any well-known manner; but it is obvious that any other motor may be employed to operate this bell-hammer when its stop is released by the synchronous action of the electric current and corresponding vibrator C, substantially as described. As, however, but little force is required to overcome the balance-weight D of the bell-crank lever, the rod q h will lift it, depressing weight s and liberating hammer F of the alarm-movement by a much less expenditure of electric force and by a much less propulsive power of the synchronously-vibrating weight m than would be required to sound an alarm by the weight m striking the bell directly, and in this way all rebounding action of the weight m while striking a bell is avoided. When the alarm is thus sounded the shaft S h of the alarm will make a part of a revolution, and the observer will be compelled to wind up the alarm to bring the circuit-breaker into position to pass through the opening O p, as the part marked h², which passes through, has a wing which must be brought over the corresponding irregularity in the opening O p. When he has done this he signals the central station—i.e., the person at the station calling—by pressing upon the knob V, Fig. 2, which, if the circuit is complete, breaks the circuit and gives an alarm at the central or other station in connection in the usual manner, and also causes a movement of the weight m, Fig. 1, in his own instrument, which movement, being observed, signifies to him that his signal is being given, and a responsive movement of

the weight, caused by the breaking of the circuit at the central station, notifies him that his signal has been received, when, the proper connections being made, the desired communication can be sent. If the operator wishes to communicate with the central office, he presses knob V, above described, as before stated. When a person wishes to signal another upon the same circuit he can do so without the intervention of the central station, provided there is a caller attached to his instrument, with a circuit-breaker that corresponds to the vibrator of the other.

It is thus obvious that by causing the electric current sent in synchronous pulsations with the vibrator C from a distant station to operate a latch or stop mechanism through the medium of C, to release and hold the bell-hammer F for striking the bell at will, I avoid in great part the probability of disturbing the synchronous movement of the vibrator C with the electric current, upon which the certainty of its operation, especially with weak currents of electricity, greatly depends. This results from the fact that the operation of such stop mechanism imposes less work upon the vibrator C than striking a bell directly, as before explained. The fundamental elements of this part of my invention are the combination of means for sending the synchronous electric current from a distant station through the magnet A, the synchronously-moving vibrator C, the stop mechanism D, and the bell-hammer F; and I do not confine myself to the specific combination of these parts I have described, as I am well aware that many modifications may be adopted which will accomplish the result I seek to obtain—*i. e.*, the maintenance with weak electric currents of the synchronosity of the vibrator C with the pulsations of such currents while causing the alarm to be sounded, thus insuring the certainty of always sounding the alarm at the station being called, and of not sounding the alarm at any other station on the circuit.

Instead of the free swinging vibrator C, any other well-known form of vibrator may be substituted which is capable of vibrating synchronously with the electric current. It is of course understood that the vibrator C is so adjusted with relation to the propulsive power of the magnet and electric current that no single impulse of electricity will bring the vibrator against the bar of the latch D sufficiently to release the bell-hammer F, and this effect is assisted by the elastic spring part k between the armature i of the magnet and the vibrator C. The successive impulses given to the armature i are transmitted by the spring k to the vibrator C, so as not to interfere with or overcome the normal rate of vibration of it, and thus when the electric pulsation and corresponding movements of the armature i are synchronous with the normal vibration of the vibrator C they con-

stantly increase the path of its motion through several successive beats until it reaches and releases the stop D. On the other hand, if the electric pulsations passing through the magnet and the corresponding movements of the armature i are not synchronous with the normal beat of the vibrator C, their transmission through the spring k will only cause the normal movements of the vibrator the instant it is started to operate against the movements of the armature i, and constantly tend to bring the vibrator to a state of rest before in its movement it has reached the bar of the stop D. Consequently electric pulsations sent over the circuit synchronous with the normal vibration of the vibrator C will cause the stop to be released and the bell sounded, while electric pulsations passing through the magnet and over the circuit, which are not synchronous with the normal movement of the vibrator, will not release the stop and sound the bell. As the different stations on the same circuit are provided with vibrators of substantially different normal rates of vibration, it is evident that only the bell of one station will be sounded by pulsations of electricity synchronous to any one of the vibrations sent over the circuit.

What I claim as new and of my invention is—

1. The combination of the magnet A and vibrator C, adapted to be normally vibrated to release the stop only by synchronous pulsations of electricity through the magnet, with the stop D and alarm-hammer F, substantially as described.

2. In combination with the magnet A, the armature i, spring k, vibrator C, stop D, and alarm-hammer F, substantially as described.

3. In combination with an electric circuit, a series of alarm mechanisms, each consisting of magnet A, vibrator C, adapted to be normally vibrated to release the stop only by synchronous pulsations of electricity through the magnet stop D, and alarm-hammer F, substantially as described.

4. In combination with an electric circuit, a series of alarm mechanisms, each consisting of the alarm-hammer F, stop D, magnet A, armature i, spring k, and vibrator C, made of a different normal beat from that of any other station, substantially as described.

5. The combination, with an electric circuit, of a circuit-breaker placed at one station, and an alarm mechanism, consisting of a magnet, vibrator, alarm-hammer, and stop, placed at another station, such vibrator being adapted to reach the stop and release the hammer only when operated by pulsations of electricity synchronous to its normal rate of vibration, substantially as described.

JACOB B. CURRIER.
